2,250,551

PUMP FOR HYDRAULIC JACKS

Edward M. Pfauser, Elm Grove, Wis., assignor to
 Blackhawk Mfg. Co., Milwaukee, Wis., a corporation of Wisconsin

Application July 1, 1938, Serial No. 216,909

7 Claims. (Cl. 103—42)

My present invention relates generally to improvements in hydraulic jacks, and relates more specifically to improvements in the construction and operation of multiple speed jacks of the type wherein the lifting head may be quickly initially positioned in contact with the work, and thereafter most effectively applied at reduced speed to actually perform its duty.

It has heretofore been proposed as shown in my prior Patent No. 1,873,473, granted August 23, 1932, to provide a hydraulic type of service jack for garages or the like, wherein the lifting head may be rapidly elevated to position the same in initial contact with the work, with the aid of a relatively large low pressure pump, and in which the load is automatically transferred to a smaller high pressure pump when the resistance to continued elevation of the head is increased. While this type of jack has proven highly practical and satisfactory in commercial use, it requires the application of considerable excess power to operate the lower pressure pump against the retarding pressure when the high pressure pump is in action during final lifting of the work. This feature is not seriously objectionable when lifting light loads, but is quite objectionable when heavy loads are being handled, because of the constant power required to actuate the speed pump, in addition to that necessary for operating the high pressure pump. In an effort to obviate this objection, I later provided a spring pressed by-pass valve in the circuit of the large low-pressure pump, loaded to a predetermined pressure, and adapted to partially relieve the pressure in the large pump when the small pump was working under high pressure, as shown in Patent No. 2,044,857, granted June 23, 1936. While this improved construction was a vast improvement over the original two speed jack, it was still somewhat objectionable since it did not entirely relieve the large pump from retarding pressure while the other pump was operating under high pressure, due to the predetermined loading of the by-pass valve.

It is therefore an object of my present invention to provide a multiple pump hydraulic jack of the general type above referred to, wherein one of the pumps is entirely relieved of retarding pressure, when the other or others are operating under high pressure.

A more specific object of the invention is to provide improved control mechanism for a hydraulic jack, which will function to automatically relieve one of a plurality of actuating

pumps from excess pressure, when another of the pumps becomes active.

Another specific object of this invention is to provide an improved unloading device for hydraulic jacks, which is automatically operable by pressure resulting from loading the jack.

These and other objects and advantages of my present invention will be apparent from the following detailed description.

A clear conception of one practical embodiment of the invention, and of the mode of constructing and of operating hydraulic jacks built in accordance with the improvement, may be had by referring to the drawing accompanying and forming a part of this specification, wherein like reference characters designate the same or similar parts in the several views.

Fig. 1 is a central longitudinal vertical section through a typical two speed hydraulic jack of the portable type;

Fig. 2 is an enlarged part sectional top view of a portion of the jack assemblage adjacent to the rear wheels; and

Fig. 3 is a similarly enlarged transverse vertical section taken through the supply reservoir and control valves of the jack.

While the invention has been shown and described herein as being embodied in a two speed portable garage-type of hydraulic jack, it is not the intention to thereby unnecessarily restrict the scope, since the improved unloading device may be more generally applicable to other types of fluid pressure actuated jacks.

Referring to the drawing, the portable hydraulic jack assemblage illustrated therein comprises, in general a horizontally elongated frame consisting of a pair of laterally spaced similar opposite side beams or plates 5, having a power unit casing 6 interposed between and rigidly attached to the rear portions of the plates 5; front supporting wheels 7 for the main frame mounted upon an axle 8; rear caster wheels 9 pivotally suspended from brackets 10 formed integral with the side plates 5; a lifting arm 11 swingably suspended at one end from the medial upper portions of the frame plates 5 by means of a pivot pin 12, the arm 11 being swingable downwardly against a stop and having a lifting head or saddle 13 pivotally supported at the opposite end thereof; a parallel motion link 14 having one end pivotally associated with the main frame and its opposite end pivotally attached to the carrier socket for the saddle 13; a motion imparting plunger 15 slidable in the casing 6 and having its outer end cooperable with

a roller 16 carried by the arm 11 remote from the pivot pin 12; a tension spring 17 for constantly urging the roller 16 in contact with the plunger 15; an oil supply reservoir 18 of ample capacity formed in the casing 6 above and laterally adjacent to the hydraulic displacement chamber 19 of the plunger 15 which is also formed in the casing 6; a high speed pump plunger 20 coacting with a bore 21 in the casing 6 and being reciprocable through links 22 by means of a handle 23 pivotally suspended from the rear of the casing 6; a pressure or slow speed pump plunger 24 rigidly attached to the casing 6 and slidably coacting with a central bore 25 formed in the reciprocable plunger 20; valve mechanism for controlling the delivery of liquid from the reservoir 18 through the pumps to the chamber 19; and a release valve 26 for permitting return of liquid from the chamber 19 to the reservoir 18 during lowering movement of the arm 11.

The general construction of the jack is well known, and constitutes no part of my present invention, and the improved valve mechanism for the pumps is clearly shown in Figs. 2 and 3. The liquid supply reservoir 18 which is formed in the power unit casing 6, is provided with two relatively deep wells 27 which are connected through strainers 28 and a horizontal passage 29, with vertical ports 30, 31 of which the large port 30 is controlled by a ball suction valve 32 while the smaller port 31 is likewise controlled by a small ball suction valve 33. The port 30 is communicable past the valve 32 and through a passage 34, with the bore 21 constituting the speed pump displacement chamber, and this displacement chamber is also communicable through a similar passage 35 with one side of a discharge valve 36 the opposite side of which communicates with the lifting plunger displacement chamber 18 through a passage 37. The valve 32 therefore constitutes the inlet or suction valve for the speed pump, while the valve 36 constitutes the outlet or discharge valve for this low pressure pump. The small port 31 is communicable past the valve 33 and through a passage 38, with the bore 25 constituting the pressure pump displacement chamber, and this chamber is also communicable past a discharge valve 39 and through a passage 40, with the plunger displacement chamber 19, independently of the connection of the speed pump therewith. The pressure release valve 26 for normally relieving the pressure from within the chamber 19, is disposed in a conduit 41 which connects the passage 40 with the reservoir 18, and the release valve 26 may be held in closed position by means of a rotary threaded spindle 42 which is operable by a rod 43 and grip-knob 44 carried by the pump actuating handle 23. With this assemblage of ball valves 26, 32, 33, 36, 39, reciprocation of the pump plunger 20 will cause liquid to be withdrawn from the reservoir 18 into the bores 21, 25 past the suction valves 32, 33 respectively; and to be delivered to the chamber 19, past the valves 36, 39 when the release valve 26 is closed, to thereby move the lifting plunger 15 in a forward direction.

The chamber 45 in which the suction valve 32 is located, and which is constantly in communication with the speed pump bore 21 through the passage 34, is provided with a limit stop member 46 and is communicable past this member with a passage 47 formed in an unloading valve casing 48. An unloading valve 49 which is normally

pressed to its seat by a spring 50, is adapted to open when the pressure in the bore 21 reaches a predetermined value, so as to permit the liquid from the speed pump to escape to the reservoir 18, thus preventing the speed pump plunger 20 from being subjected to pressure above a definite predetermined value, at any time. While the spring 50 determines the maximum pressure to which the speed pump plunger 20 can be subjected, the valve 49 is also adapted to be positively opened and to be held in open position so as to further relieve the pressure within the bore 21, when the pressure pump is effective in lifting the work, by means of a piston 51 slideable in a bore 52 in the casing 48 and having a stem 53 adapted to engage the ball valve 49. One face of the piston 51 is exposed to the displacement chamber 19 through a conduit 54, and the opposite side of the piston 51 forms a poppet valve and coacts with a spring 55 which embraces the stem 53, and the tension of the spring 55 is preferably sufficient to prevent the stem 53 from engaging the valve 49 until after the pressure in the bore 21 has become sufficient to intermittently unseat this valve as the plunger 20 reciprocates. When the piston 51 is in its extreme lower position, the lower face seats against the tapered seating on the casing 48 and prevents high pressure fluid from escaping past the piston. The unloading device therefore functions to positively unseat the valve 49 and to hold it open, when the pressure in the displacement chamber 19 and conduit 54 is sufficient to move the piston 51 against the action of the spring 55 to a position wherein the stem 53 will engage and unseat the valve 49; and when the pressure in the chamber 19 falls below the predetermined value fixed by the tension of the spring 55, then the spring 50 immediately becomes effective.

The chamber 56 within which the discharge valve 36 is located, and which is in constant communication with the displacement chamber 19 through the passage 37, is likewise provided with a limit stop member 57 and is communicable past this member with a passage 58 formed in a safety valve casing 59. A poppet type of safety valve 60 is mounted in the casing 59 and is normally held to its seat by means of a coil spring 61 which is of sufficient strength to establish a predetermined high pressure within the chamber 19. When this maximum pressure is exceeded, the safety valve 60 will automatically open to permit liquid to escape from the chamber 19 through the passage 37, chamber 56 and passage 58 to the reservoir 18. The chamber 62 within which the pressure pump discharge valve 39 is located, is also provided with a limit stop member 63, and the valves 32, 33, 36, 39, 49 are obviously accessible for inspection upon removal of their normal confining members. The liquid supply reservoir 18 is provided with a removable cover 64, and all of the plungers 15, 20, 24 are provided with suitable packings adapted to be lubricated by the liquid such as oil from the reservoir 18.

During normal use of the improved jack assemblage, and when the device is not in actual operation, the plug 42 is withdrawn to permit free opening of the release valve 26, and the lifting arm 11 is in lowered position resting against the frame stops. The lifting ram or plunger 15 will then be pushed rearwardly into the displacement chamber 19, and the handle 23 and pump plunger 20 may be either in the position shown in Fig. 1 or in any other desired post-

tion. If it becomes desirable to elevate the arm 11 and saddle 13, it is only necessary to turn the knob 44 to positively close the release valve 26 with the aid of the plug 42, and to thereafter oscillate the handle 23 so as to reciprocate the speed pump plunger 20 through the links 22. The plunger 20 during its rearward stroke will then draw liquid from the reservoir 18 through the passages 29, 36 past the suction valve 32, and through the chamber 45 and passage 34 into the bore 21; and during the forward stroke, the plunger 20 will force this liquid through the passage 35 past the discharge valve 36, and through the chamber 56 and passage 37 into the lifting plunger chamber 19, providing no work is being engaged by the saddle 13. During this initial reciprocation of the plunger 20, liquid will also be drawn from the reservoir 18 through the passages 29, 31 past the small suction valve 33, and through the passage 38 into the pressure pump bore 25 during the rearward stroke of the plunger 20; and will be forced by the fixed plunger 24 out of the bore 25 through the passage 38 past the discharge valve 39, and through the passage 40 into the chamber 19 during the forward stroke of the plunger 20. This combined delivery of liquid by both the speed and the pressure pump, to the displacement chamber 19, obviously causes the plunger 15 to move forwardly at a rapid rate, and quickly lifts the arm 11 and saddle 13 until the latter engages an obstruction.

When the saddle 13 is subjected to excess pressure such as an object which is to be elevated, the hydraulic pressure within the chamber 19 is quickly increased by the ram or plunger 15, and subsequent forward movement of the plunger 20 will augment this pressure, and will cause the valve 49 to be automatically opened against the action of the spring 50. The increase in pressure in the chamber 19 will be transmitted through the conduit 54 to the piston 51, and will force the latter downwardly against the action of the spring 55 until the piston seats against the casing 48 and the stem 53 unseats the valve 49 and holds the same open. The valve 49 will then be held open as long as the pressure in the chamber 19 and connection 54 is sufficient to produce such action, but when this pressure drops so as to enable the spring 55 to elevate the stem 53 out of contact with the casing seating and valve 49, this valve will again be seated by the spring 50. When the valve 49 is thus opened, the large annular face of the plunger 20 which surrounds the fixed plunger 24, will obviously be entirely relieved of pressure, and will thus permit oscillation of the handle 23 with minimum effort.

After the saddle 13 has engaged the work, the pressure pump continues its delivery of liquid from the reservoir 18 into the displacement chamber 19, and the lifting plunger 15 will continue to travel forwardly but at a considerably reduced rate of speed. If, however, the pressure in the chamber 19 reaches the maximum value fixed by the spring 61 of the safety valve 60, then the valve 60 will be opened by this high pressure acting through the passage 37, chamber 56 and passage 58, and excess pressure will be relieved to the reservoir 18. While the plunger 20 is at all times subjected to the pressure prevailing within the small bore 25 this pressure alone can never reach a value sufficiently high to prevent the operator from oscillating the handle 23, or to cause breakage of parts, by virtue of the provision of the safety valve 60. It will be apparent, however, that the release of the pres-

sure within the bore 21 when the work is being lifted, reduces the force required to oscillate the handle 23 to a minimum when the pressure pump is active in lifting objects, and the improved unloading device obviously functions to quickly relieve the larger area of the plunger 20 from excessive pressure when the saddle 13 engages the work. In order to subsequently lower the arm 11 and the saddle 13, it is only necessary to manipulate the knob 44 so as to withdraw the plug 42 and release the valve 26, whereupon the liquid from within the chamber 19 returns to the reservoir 18 through the passages 40, 41.

From the foregoing detailed description it will be apparent that my present invention provides an extremely simple yet highly effective unloading device for multiple speed hydraulic jacks, which effectively relieves the actuating handle from excessive pressure due to the continued operation of the speed pump while work is being performed with the jack. The unloading piston 51 is rapid and automatic in its action by virtue of its being exposed to the interior of the chamber 19 at all times, and when the valve 49 is unseated or opened, the speed pump is made inactive without interfering with the normal operation of the pressure pump. It will be apparent that the release of this pressure acting on the relatively large area of the speed pump will materially reduce the effort necessary to actuate the pressure pump when extremely heavy objects are being lifted with the jack, and the present improvement has proven highly satisfactory in actual use and may obviously be conveniently applied to hydraulic jacks of the general type shown herein with the addition of very few and relatively inexpensive parts.

It should be understood that it is not desired to limit this invention to the exact details of construction or to the precise mode of use, herein shown and described, for various modifications within the scope of the claims may occur to persons skilled in the art.

I claim:

- 45 1. In combination, a large displacement pump, a small displacement pump, means for simultaneously operating said pumps, means forming a space for receiving fluid from both pumps, a fluid supply reservoir, an unloading valve interposed between said reservoir and the displacement chamber of said large pump, said valve being operable directly by excessive pressure in said chamber to permit escape of fluid to said reservoir, and a plunger operable by pressure in said space to open said valve.
- 50 2. In combination, a large displacement pump, a small displacement pump, means for simultaneously operating said pumps with equal strokes, means forming a space for receiving liquid from both pumps, a liquid supply reservoir, a spring seated unloading valve interposed between said reservoir and the displacement chamber of said large pump, said valve normally being movable in opposition to its seating spring directly by excessive pressure in said chamber to permit escape of liquid to said reservoir, and a spring restrained plunger operable by excessive pressure in said space to open said valve independently of the pressure in said chamber.
- 55 3. In combination, a large displacement pump, a small displacement pump, said pumps having coaxial pistons and cylinders and being simultaneously operable with equal strokes, means forming a space for receiving liquid from both pumps, a liquid supply reservoir, an unloading

valve normally operable by excessive pressure in the displacement chamber of said large pump to permit escape of liquid from said chamber to said reservoir, and means operable only by excessive pressure in said space to open said valve independently of the pressure in said chamber.

4. In combination, a large displacement pump, a small displacement pump, said pumps having coaxial pistons and cylinders and being simultaneously operable with equal strokes, means forming a space for receiving liquid from both pumps, a liquid supply reservoir, a spring seated unloading valve normally operable by excessive pressure in the displacement chamber of said large pump to permit escape of liquid from said chamber to said reservoir, and a spring restrained plunger operable only by excessive pressure in said space to open said valve independently of the pressure in said chamber.

5. In combination, a large displacement pump, a small displacement pump, said pumps having simultaneously operable coaxial pistons, means forming a space for receiving liquid from both of said pumps past their respective discharge valves, a liquid supply reservoir communicable with both of said pumps past their respective inlet valves, an unloading valve normally operable only by excessive pressure in the displacement chamber of said large pump to permit escape of liquid from said chamber to said reservoir, and a 30

plunger constantly exposed to the pressure in said space and being operable by excessive pressure in the latter to open said unloading valve independently of the pressure in the displacement chambers of said pumps.

6. In combination, a large displacement pump, a small displacement pump, means for simultaneously operating said pumps, means forming a space for receiving fluid from both pumps, a 10 fluid supply reservoir, a poppet type unloading valve interposed between said reservoir and the displacement chamber of said large pump, said valve being operable directly by excessive pressure in said chamber to permit escape of fluid to said reservoir, and movable means operable by pressure in said space to open said valve.

7. In combination, a large displacement pump, a small displacement pump, means for simultaneously operating said pumps, means forming a space for receiving liquid from both pumps, a liquid supply reservoir, a spring seated poppet type unloading valve interposed between said reservoir and the displacement chamber of said large pump, said valve normally being movable in opposition to its seating spring directly by excessive pressure in said chamber to permit escape of liquid to said reservoir, and a spring restrained plunger operable by excessive pressure in said space to open said valve.

EDWARD M. PFAUSER.
